UNITED STATES PATENT OFFICE.

JAMES A. NORTON, OF ODEBOLT, IOWA.

ENGINE.

SPECIFICATION forming part of Letters Patent No. 762,189, dated June 7, 1904.

Application filed June 22, 1903. Serial No. 162,511. (No model.)

To all whom it may concern:

Be it known that I, JAMES A. NORTON, a citizen of the United States, residing at Odebolt, in the county of Sac and State of Iowa, have invented new and useful Improvements 5 in Engines, of which the following is a specification, reference being had to the accompanying drawings, forming a part thereof:

The purpose of this invention is to provide 10 an improved engine to be operated by any expansive fluid, whether steam, hot air, or gas, which shall be especially advantageous in respect to compactness and symmetry relatively to the power developed and specifically which 15 shall be approximately balanced as to distribution of its weight on opposite sides of the main shaft to adapt it to use as a motive power in boats and launches, in which a plurality of such engines may be assembled side by side, 20 operating on a common fore-and-aft main shaft, or in other situations in which a plurality of motors may be desired for operation on a common shaft with the facility for using one or any greater number of them, as the 25 work may require.

It consists in the features of construction which are set out in the claims.

In the drawings, Figure 1 is a side elevation of my improved engine. Fig. 2 is an 30 elevation of the opposite side, certain parts being partly broken away to disclose the interior features. Fig. 3 is an end elevation of the same. Fig. 4 is a section at the line 4 4 on Fig. 1.

35 Rigid with a base or standard 1 I form two cylinders 2 and 3, one above the other, having their chambers separated by a sufficient distance to permit the main shaft 4 to obtain bearing at 5, through which it extends trans- 40 versely between the cylinders, as seen in Fig. 4. The pistons 6 6 in the cylinders 2 and 3, respectively, have their rods 7 7 connected at their opposite ends by cross-heads 8 8, so that the two pistons operate synchronously in their 45 respective cylinders. The pistons communicate rotary motion to the main shaft 4 by means of clutches on said shaft at opposite ends of the bearing 5. These clutches each comprise an interior element 9, rigid with the 50 shaft, and an exterior element or drum 10, loose on the shaft, which is connected with the pistons for actuation. The upper piston has for that purpose rigid with it the bar 11, parallel with the piston-rod and carried rigidly therewith by means of the arms 12 12, 55 jutting off from the upper end of the cross-heads 8 8, respectively. Similarly the lower piston carries rigidly a parallel rod 13, secured by means of the arms 14 14, jutting off from the cross-heads at their lower end. The bar 11 is 60 connected with the exterior element 10 of the clutch at one end of the bearing 5 by means of flexible cables or chains 15 15, which are attached, each at one end, to the rod and wrapped in opposite directions on the drum 10 65 over the upper side thereof, and in like manner the rod 13 is connected by similar flexible cables or chains 15 with the other drum 10, about which said chains lap in opposite directions on the lower side. The construction 70 of the clutches may be understood from Fig. 3, comprising, between the two elements 9 and 10, the clutch-balls 16, lodged in the pockets formed in the periphery of the element 9 and adapted to clamp the two elements 9 and 75 10 together when the outer element is revolved in direction to pinch the balls in the pockets and to permit free rotation of the outer element in the opposite direction by releasing the balls, all in a manner well understood. The 80 two clutches have their pockets constructed and balls arranged so as to communicate rotary motion to the shaft both in the same direction; but one being actuated at the lower side and the other at the upper side it will be 85 seen that the stroke of the pistons in one direction causes one clutch to drive the shaft, while the other rotates idly about it, and the stroke of the pistons in the opposite direction causes the clutch which idled in the first stroke 90 to continue the rotation of the shaft while the first clutch rotates idly. Thus the rotation of the shaft continuously in the same direction results from the reciprocation of the two pistons together. It will be noticed that the 95 structure is symmetrical about the vertical axial plane of the shaft 4 and that the entire length of the structure over all parts is substantially only double the length of the cylinder, and the total space required for the ac- 100

tion, including the stroke of the pistons, from the extreme position in one direction to the extreme position in the opposite direction is about three times the length of the stroke 5 only, and this compactness is due to the construction by which the main shaft is journaled transversely between the two cylinders.

In respect to the valve action of this engine it is identical with my application, Serial No. 147,392, filed March 12, 1903, and this action need therefore be described only briefly. The motive fluid is controlled in its admission to and discharge from the cylinders by piston-valves 27 27, which operate in chambers 17 17, 15 parallel with the cylinders, respectively, both at the same side, said valve-chambers being sufficiently separated vertically to leave room for one of the clutches between them, as seen in Figs. 3 and 4. The two valve-stems are 20 connected at their opposite ends by cross-heads 18 18, and these cross-heads are in turn connected by the bars 19 19, between which the main shaft 4 extends and which carry on the short cross-necks 20 20 the abutments 25 21, upon which the valve-operating cam 22 acts as the shaft revolves, said cam being carried rigidly by the shaft 4 and having the element 23 adjustable with respect to the main portion to vary the angular distance between 30 the slopes which operate to shift the valves for admission and cut-off of the steam, and thereby to vary the point of cut-off in the stroke, as fully explained in my said pending application. The live steam may be admitted to 35 the valve-chambers and the exhaust-steam discharged therefrom through passages formed in any convenient relation to these valve-chambers, as illustrated, the live steam which is admitted at the connection 24 at one end and finds 40 its way by passages 25 25, leading round the bearing 5 to the upper and lower piston-chambers, respectively, and the exhaust-steam is discharged from said chambers at both ends through ports 26, which may for convenience 45 be connected by exterior pipes (not shown) for conducting the exhaust to a convenient point for its discharge into the atmosphere.

I claim—

1. An engine comprising two cylinders rigid 5 and parallel with each other; pistons operating synchronously in said cylinders, and for such operation rigidly connected outside the cylinders; a main shaft extending between the cylinders transversely thereto; two clutches 10 on said shaft comprising each a fast and a loose element, both clutches being adapted to rotate the shaft in the same direction and to have the loose element idle thereabout in the opposite direction, the loose elements of said 15 clutches being connected for oscillation respectively at opposite sides of the axis of the shaft.

2. An engine comprising two cylinders rigid 65 and parallel with each other; pistons operating synchronously in said cylinders, and for

such operation rigidly connected outside the cylinders; a main shaft extending between the cylinders transversely thereto; two clutches on said shaft, both adapted to rotate the shaft in the same direction and to idle thereabout 70 in the opposite direction, the outer elements of said clutches being connected for oscillation with the pistons at opposite sides of the axis of said outer elements respectively.

3. An engine comprising two parallel cylinders mounted rigidly with each other; a main shaft extending transversely within them; pistons in said cylinders having their respective rods rigidly connected outside the cylinders for synchronous action; two clutches on the 80 shaft, both adapted to rotate the shaft in the same direction and idle thereabout in the opposite direction; rods parallel with the pistons extending on opposite sides of the shaft-axis and rigidly connected with the pistons 85 outside the cylinders, the outer elements of said clutches being in the form of cylindrical drums, one of said rods being connected with one of said drums at one side of the axis, and the other being connected with the other drum 90 at the other side of the axis for oscillation of said drums as the pistons reciprocate.

4. An engine comprising two parallel cylinders mounted rigid with each other; a main shaft extending transversely between them; 95 pistons in the cylinders respectively, having their rods rigidly connected outside the cylinders for synchronous action; two clutches on the shaft, both adapted to rotate it in the same direction and to idle about it in the opposite direction; two supplemental rods rigid with the piston-rods extending outside the cylinders at opposite sides of the shaft, the exterior elements of said clutches consisting of cylindrical drums, each of said supplemental rods 105 being connected to one of the drums for oscillation as the rod reciprocates; flexible chains or cables which make such connection attached respectively to the rod at points remote from each other and lapped about the drums in opposite directions.

5. An engine comprising two parallel cylinders mounted rigid with each other; a main shaft extending and having its bearing transversely between them; pistons in said cylinders 115 respectively having their rods rigidly connected outside the cylinders for synchronous action; clutches on the shaft at the opposite ends of said bearing and opposite sides of the cylinders, both adapted to rotate the shaft in the same direction and to idle thereabout in the opposite direction; rods parallel with the piston-rods at opposite sides of the cylinders extending past the peripheries of said clutches 120 at opposite sides of the shaft, and means connecting said rods with the exterior elements of said clutches respectively for oscillation of the latter as the pistons and rods reciprocate.

6. An engine comprising two cylinders rigid and parallel with each other; pistons operat- 130

ing synchronously in said cylinders, and for such operation rigidly connected outside the cylinders; a main shaft extending between the cylinders transversely thereto, and two 5 clutches on said shaft comprising each a fast and loose element.

7. An engine comprising two cylinders rigid and parallel with each other; pistons operating synchronously in said cylinders, and for 10 such operation rigidly connected outside the cylinders; a main shaft extending between the cylinders transversely thereto, and two clutches on said shaft comprising each a fast and loose element, and connections from the 15 pistons to the loose elements of said clutches respectively at opposite sides of the shaft.

8. An engine comprising two cylinders rigid and parallel with each other; pistons operating synchronously in said cylinders, and for 20 such operation rigidly connected outside the cylinders; a main shaft extending between

the cylinders transversely thereto, and two clutches on said shaft.

9. An engine comprising two cylinders rigid and parallel with each other; pistons operating synchronously in said cylinders, and for such operation rigidly connected outside the cylinders; a main shaft extending between the cylinders transversely thereto; two clutches 25 on said shaft, each comprising an interior element fast on the shaft, and an exterior element, and connections from the pistons to said exterior elements respectively at opposite sides of the shaft.

In testimony whereof I have hereunto set 30 my hand, in the presence of two witnesses, at Odebolt, Iowa, this 18th day of June, 1903.

JAMES A. NORTON.
